DRAFTING INSTRUMENT

Jeremiah W. Albin, Babylon, N. Y., assignor of twenty-five per cent to William M. Muney, Providence, R. I.

Application December 8, 1936, Serial No. 114,743

3 Claims. (Cl. 33—27)

The present invention relates to a marking or drawing instrument and particularly relates to an instrument for marking or drawing geometrical figures upon paper, wood, glass, and so forth. It is among the objects of the present invention to provide an inexpensive, readily manipulated drawing instrument designed for drawing various geometrical figures, such as ellipses, polygons or other regularly or irregularly shaped objects, and so forth on paper or other surfaces and also designed to mark or cut glass with such figures.

Another object is to provide a drawing instrument of the character above described which may be readily operated to place a large variety of figures upon a desired surface by relatively simple manipulations and without difficulty in adjustment.

Other objects will appear or will be obvious during the course of the following specifications.

In accomplishing the above objects, it has been found most convenient to provide a standard, preferably including three legs, two of these legs may carry a plurality of transverse structures, one structure supporting a marking or writing instrument and the other structure guiding said instrument, the guiding structure preferably being positioned below the supporting structure.

One of the three legs may be detachable and the guiding structure may be so assembled on the legs that its height in respect to the table or support may be varied.

In one form of construction, the stylus, pencil, pen or other marking device is provided with a resilient connection to the upper supporting structure which enables the device to be drawn downwardly to make contact at its lower point with the object to be marked.

The guiding structure is preferably provided with a recess or holder in which may be positioned plates having differently shaped apertures, these apertures, for example, taking the form of ellipses, triangles, and so forth.

The above and other objects will appear more clearly from the following detailed description when taken in connection with the accompanying drawings and will illustrate a preferred embodiment of the inventive idea.

In the drawings:

Figure 1 is a front elevation of one form of apparatus according to the present invention.

Figure 2 is a side sectional view upon the line 2—2 of Figure 1;

Figure 3 is a transverse sectional view upon the line 3—3 of Figure 1;

Figure 4 is a transverse sectional view upon

the line 4—4 of Figure 2 with the supporting leg partly broken away.

Figure 5 illustrates upon an enlarged scale, in side view and partly in section, an inking or ruling pen which may be utilized in lieu of the pencil in the combination of Figs. 1, 2 and 3.

Figure 6 is a transverse sectional view upon the line 6—6 of Figure 5 upon an enlarged scale.

Figure 7 is a plan view upon an enlarged scale of an alternative outline arrangement designed to be used in place of the arrangement shown in Figure 3;

Figure 8 is a plan view of a further alternative guiding outline designed to be utilized in lieu of the arrangement shown in Figure 3 also upon an enlarged scale.

Figure 9 is a front elevational view of an alternative construction designed for marking glass.

Figure 10 is a fragmentary side view, partly in section and upon an enlarged scale, of the lower end of the marking device of Figure 9, and

Figure 11 is a side view partly in section and upon an enlarged scale of an alternative marking device designed to carry a supply of marking fluid.

Figure 12 is a side view of a marking device attachment for use with leads or crayons.

Referring to Figures 1 to 4, the device is provided with a standard A having vertical legs B and a supporting leg C. The legs B are joined at their upper ends by the cross bar D. The marking device E is suspended from the bar D and passes through the guide frame F.

The legs B are pointed at their lower ends 10, where they rest on the table 11. Upon the legs B are received the sleeves 12 which slide upon the legs and are fixed in any desired position by the set screw 13 having an enlarged head 14.

The upper ends of the legs are of reduced diameter as indicated at 15 and a cross member D is provided with openings to fit upon said reduced diameter portions 15 and rest upon the shoulders 17. The nuts 18 are designed to clamp the cross member D in position upon the top of the legs B.

The sleeves 12 at their lower ends are rigidly fitted onto the cross member F which is of skeleton construction, as best shown in Fig. 3.

The cross member F has side arms 19 which support the square frame portion 20. The square frame 20, as best shown in Fig. 2, is shouldered at 21 to receive the guide plate 22.

The back of the frame 20 is provided with an opening 23 which receives the projecting end 24 of the spring holder or clip 25. The opposite side of the frame 20 is also provided with an opening 26 through which projects the grip portions 27. The grip portions 27 fit under the overhanging portions 28 (see Fig. 3) so as to lock the clips 25 in position.

The plate 22 as shown in Fig. 3 has an opening 30 of an elliptical form designed to permit drawing of elliptical figures, but it is apparent that other plates, such as the plate 22a of Fig. 7 with an hexagonal opening 30a or the plate 22b of Fig. 8 with the triangular opening 30b may be employed. The set screw 14 when loosened permits the structure F to be elevated or depressed upon the legs B.

The higher the cross member F the larger the design will be. The exact height of the cross section F may be determined by a graduated scale 31 (see Fig. 1) positioned on one of the legs B as shown in Fig. 1.

The cross member D is provided with a conical recess 32, through which projects the upper portion 42 of the marking device E. The marking device E is headed with the screw 34. The coil spring 35, encircling the device E reacts against the head 34 at its upper end and against the washer 36 at its lower end.

30 The device E is also provided with a stop enlargement 37 which prevents it from being lifted out of the recess 32.

The lower end 37 of the marking device E is interchangeable. This is accomplished by the 35 tapped socket 38 which received a threaded projection 39 from the lower end portion 40 of the marking device E. The device E as shown in Fig. 1 has a pencil point 41. The lower end of the upper shank 42 of the marking device E abuts the lower portion 40 at 43 as shown in Fig. 2.

To enable a firmer support of the structure A upon a table 11, an additional leg C is provided as best shown in Fig. 2. The lower end of the 45 leg C is pointed as indicated at 44 to contact the table. The upper end of the leg C is flattened and bevelled as indicated at 45 in Fig. 4. This flattened and bevelled portion 45 fits into the recess 46 in the cross member D.

50 In operation the marking device E may be grasped by the fingers M as indicated in Fig. 1 and moved downwardly from the position of Fig. 2 until the pencil point 41 touches the paper or other sheet to be marked upon the table 11. 55 The device E then may be moved around contacting the edge of the opening 30 as indicated at P—P in Figs. 1 and 2 with the result that an ellipse will be formed, the size of which may be regulated by the position of the guide structure F in respect to the scale 31.

60 As soon as the marking device is released it will be moved back into the original position of Fig. 2 by the spring 35.

The conical opening 32 in the cross member 65 D permits free movement of the device E. The plates 22 may be changed by bringing together the finger grip portions 27, removing the locking wire 25 and then lifting the plate 22 out of position. Other plates 22 with other shaped openings 70 30 may then be substituted and the locking wire 25 be replaced.

To remove the guide structure F, it is necessary to remove the lock nut 47 which fits upon the threaded lower end 48 of one of the legs B. 75 With the nut 47 removed and the set screw 13

loosened, the entire structure F may slide off the legs 13. The wedge 45 of the leg C may be readily inserted into or removed from the wedge-shaped opening 46 which converges upwardly. To remove the device E, the screw 34 may be 5 loosened and the marking device E may be removed. However, it is usually sufficient to break the connection 38—39 and replace the pencil 40 as shown in Figs. 5 and 6 with some other marking device.

10 As indicated in Figs. 5 and 6, the threaded shank 39 of the pen 40' may be threaded into the tapped recess 38 of the marking device E. The pen 40' is provided with nibs 50 which may be adjusted by set screw 51. To enable flow of 15 ink when the pen is turned completely around, the sides of the pen are beveled as indicated at 52. This will permit ink to flow from the pen even when it is moved transversely to the nibs 50 in the direction of the arrow 53.

20 In Fig. 9 is shown a device designed for use in marking, cutting or stretching glass, similar in construction to Fig. 1, with similarly functioning parts being indicated by the same numerals provided with a superior 2.

25 In Figure 9 the plate 22² is bolted into position by the screws 25² upon the frame 20².

The bottom of the legs B² are provided with adjustable rests 10² having screws 54 permitting adjustment thereof. The leg structure B² and 30 guide structure F² are made more rugged than in Figure 1. The glass panel to be marked is indicated at 55. Instead of a pencil or a pen, the cutting wheel 56 is employed which wheel is 35 axially mounted at the bottom of the tapered portion 57 of the structure 40² on the axis 90 (see Figure 10).

40 In Figure 11 is shown an alternative marking point. The structure 40³ carries at its lower end a swinging structure 58 pivotally mounted by the 45 rod 59. The structure 58 is provided with a well 60 receiving the ink or other marking fluid from which ink is fed to a wheel 61 pivotally mounted on 62 below the cup 60. The ink may readily flow from the cup 60 to the wheel 61 and thence 45 to the surface to be marked.

50 The alternative construction of Figure 12 which may be made interchangeable with the pencil end of Figure 2 or the pen end of Figure 5, has a threaded shank 91 designed to be screwed into the tapped hole 38 in the upper portion 42 of the marking device E.

55 The gripping device 92 is split at 93 to form the jaws 94, 95 which jaws may be drawn together by the screw 96.

The screw 96 has a shank 97 which extends through the jaw 94 into the jaw 95.

60 The adjacent faces of the jaws 95, 96 are provided with grooves 98, 99 in which the lead 100 may be placed and gripped by tightening the screw 96.

65 The grooves 98 and 99 are contained through the shank 91 of the device by the bore 101, which bore is preferably placed off center so that they will not conflict with the shank 97 of the 65 screw 96.

70 The enlarged bore 102 increases the flexibility of the jaws 94 and 95 so that they may be more readily pressed together by the screw 96 to grip the lead 100.

75 Instead of a lead 100, it is also possible to use cylinders or crayons or other marking materials.

75 Although the cross bar D and legs B are shown as being made of separate parts in Figure 1, it

is apparent that they could be made of one piece of metal stock as for example, by casting.

Moreover, the swinging construction of Figure 11 might also be applied to the pen of Figure 5 5 so that the space 103 between the nibs 50 of Figure 6 would always be parallel to the direction of movement.

The height of the sleeves 12 are such that the cross bar F cannot come closer to the cross bar 10 D than indicated by the dot and dash line 110 of Figure 1.

By so proportioning the sleeve 12 assurance is had that even at the uppermost position of the cross bar F, the movement of the marking device 15 vice E will be so restricted that it cannot be extended beyond the legs 10.

The angle of the bevel 32 in the cross structure D at the top of the device, as shown in Figures 1 and 2 is sufficient so that it will fully accommodate the extreme sidewise movements of 20 the marking device E at the uppermost position of the cross member F, without jamming.

It is apparent that the specific illustrations shown above have been given by way of illustration and not by way of limitation and that the structures above described are subject to wide variation and modification without departing from the scope or intent of the invention, all of 25 which variations and modifications are to be included within the scope of the present invention.

What is claimed is:

1. A marking instrument comprising a stand comprising a plurality of legs, a supporting member carried by said legs and a guiding member 35 carried by said legs, and a marking member suspended from said supporting member and guided by said guiding member, said guiding member including a frame, an apertured guiding plate positioned in said frame and a spring clip to hold 40 said apertured plate in position.

2. A drawing instrument for marking geometrical figures upon paper, glass or other surfaces and designed to enable utilization of a pencil, pen or stylus as a marking device, said instrument comprising two vertical legs, the lower ends 5 of which are pointed for purposes of support and the upper ends of which are provided with a cross bar rigidly connected to the legs, a third leg detachably connected to said cross bar and extending to one side of said two legs, a central 10 aperture through said cross bar, a marking device extending downwardly through said aperture having an enlarged head, a coil spring encircling the upper end of said device and reacting between said cross bar and said enlarged 15 head, a cross frame, the ends of which are provided with sleeves, encircling and sliding on said first mentioned legs, a set screw to fix the position of said cross frame on said first mentioned legs, a central holder in said cross frame 20 positioned directly below said central aperture and said cross bar, said holder being shouldered so as to receive an aperture plate, said plate being apertured to form a geometrical figure and a spring clip holding said plate removably in 25 position.

3. A marking instrument comprising a stand comprising a plurality of legs, a supporting member carried by said legs and a movable guiding member carried by said legs, and a movable 30 marking member suspended from said supporting member and guided by said guiding member, said guiding member being provided with spacer sleeves also carried by said legs to limit movement thereof toward said supporting member so 35 as to prevent jamming of the marking member or movement of the marking member beyond said legs.

JEREMIAH W. ALBIN.
